UNITED STATES PATENT OFFICE.

WINFRED MUDGE BROOKS, OF EAST ORANGE, NEW JERSEY, ASSIGNOR TO E. J. BROOKS
& CO., OF NEW YORK, N. Y., A CORPORATION OF NEW YORK.

BOX-STRAP SEAL.

1,251,858.

Specification of Letters Patent.

Patented Jan. 1, 1918.

Application filed October 15, 1917. Serial No. 196,652.

To all whom it may concern:

Be it known that I, WINFRED MUDGE BROOKS, a citizen of the United States of America, and a resident of East Orange, in 5 the State of New Jersey, (whose post-office address is #93 Arlington avenue, East Orange, N. J.,) have invented certain new and useful Improvements in Box-Strap Seals, of which the following is a specification.

This invention relates to that class of protective seals and guides, which used with non-resilient metal box straps are adapted to secure and protect all the planks of a 15 packing case against surreptitious removal.

The object of the present invention is to afford through a novel combination of parts hereinafter more fully specified, a device adapted to guide, secure and seal the box 20 strap to each individual plank of the box, so that the accidental breakage of the box strap at any point would not affect the strap at other points beyond the adjacent seals. Other objects will be indicated in connection 25 with the detailed description of the invention.

One sheet of drawings accompanies this specification as part thereof, in which like reference characters denote like parts in 30 all of the figures.

Figure 1 represents a packing case secured by two box straps and a plurality of the seals described herein; Fig. 2 is a top view of an improved seal engaged with the two ends of 35 a box strap preliminary to sealing; Fig. 3 is an end view of the seal without the box strap; Fig. 4 is a cross section view taken on the line M, M, of Fig. 2; Fig. 5 is a view similar to Fig. 4 after sealing.

40 The improved seal is constructed of one piece of non-resilient sheet metal and has a flat base *a*, in which is cut two parallel slots *h*, *h*. Nail holes *c*, *c*, are cut in the base part *a* adjacent to each of the slots *h*, *h*, and the 45 part *d* between the two slots is raised in a plane above, but parallel with that of the base. A small hole *e* is punched downward near the center of the raised part *d* producing a slight downwardly projecting bur *i*.

50 In operation one of the improved seals is secured to each plank of the box to be

sealed by nails passing through the nail holes *c*. A box strap *b* is then passed over the nail heads, through the slot *h*, and under the top part *d* of each seal, both ends being 55 drawn through one seal at their junction.

Each seal is then sealed by punching downwardly through the central hole *e* with a suitable punch adapted to enlarge said hole, depress said raised part *d* into close 60 contact with the strap or strap ends beneath, and perforate the box strap or strap ends beneath the central hole *c* producing downwardly projecting burs *i* on said strap or strap ends in close interlocking engagement 65 with the enlarged bur *i* on the top part *d* as indicated in Fig. 5.

The box strap by this sealing operation is brought into a close interlocked relation with the seal part and the nails securing the seal 70 part to the plank are concealed and protected by the box strap.

Having thus fully described my invention, I claim:

An improved guide-seal for box straps, 75 constructed of one piece sheet metal and having in combination, a flat base part, two parallel slots cut in said base, nail holes in said base adjacent to said slots, a flat raised part between said slots, said raised part being above but in a plane parallel with said base and having a central hole punched therein with downwardly projecting burs, 80 said guide seal being adapted to be secured by nails through said nail holes in its base 85 to a plank of a box, to have a metal box strap, or strap ends, passed over the heads of such nails, through said slots and under said raised part and then to be sealed and permanently interlocked with said box strap. 90 or strap ends, by having said raised part with its downwardly projecting bur stamped down upon said strap, or strap ends, while a punch driven through said central hole is further driven through the strap, or strap 95 ends, producing closely interlocked burs, all substantially as hereinbefore specified.

WINFRED MUDGE BROOKS.
